UNITED STATES PATENT OFFICE.

ALBERT P. BALL, OF DETROIT, MICHIGAN.

DESIGN FOR A POKER-SET STAND.

Application filed December 9, 1926. Serial No. 19,988. Term of patent 3½ years.

To all whom it may concern:

Be it known that I, ALBERT P. BALL, a subject of the King of Great Britain, and a resident of Detroit, county of Wayne, and State of Michigan, have invented a new, original, and ornamental Design for a Poker-Set Stand, of which the following is a specification, reference being made to the accompanying drawing, forming a part thereof.

In the drawing:

I claim:

The ornamental design for a poker set stand as shown.

ALBERT P. BALL.
